Louis E. F. Wachter

UNITED STATES PATENT OFFICE.

LOUIS E. F. WACHTER, OF NEW YORK, N. Y.

WATCH-CRYSTAL.

1,304,421.

Specification of Letters Patent. Patented May 20, 1919.

Application filed November 13, 1918. Serial No. 362,408.

To all whom it may concern:

Be it known that I, LOUIS E. F. WACHTER, a citizen of the United States, and a resident of New York city, county of New York, and State of New York, have invented certain new and useful Improvements in Watch-Crystals, of which the following is a specification.

This invention relates to crystals for the protection of the hands and dials of watches, clocks and other instruments.

Prior to my invention crystals have been made of various transparent materials, the two most commonly used being glass and celluloid. The glass crystal is very hard and not easily scratched. As a consequence it retains its transparent quality. It is, however, easily broken. The celluloid crystal on the other hand is practically unbreakable but has the disadvantage of being easily scratched, and thus decreasing its transparency.

The object of my invention is to produce a closure for the faces of watches, clocks and other instruments which will have an outer surface that will not scratch, and one which can not be so broken as to expose the hands and dial which it protects.

With these and other objects in view my invention comprises the forming of a crystal having its outer surface composed of glass or similar hard, transparent, mar-resisting material, and beneath it a thickness of celluloid or other similar transparent, flexible, substantially non-breakable material.

My invention further consists in a means by which the two portions of the crystal may be so arranged as to be mounted in an ordinary bezel without any modification thereof.

With these and other objects in view my invention consists in certain constructions, combinations and arrangements of parts, a few of the forms of which will be first described in connection with the accompanying drawings, and then the invention particularly pointed out in the appended claims.

Referring to the drawings wherein the same reference numeral is used to indicate the same part wherever it occurs,

Figure 1 is a central longitudinal cross section of a crystal embodying one form of my invention;

Fig. 2 is a similar view of a slight modification in the means of attaching the two portions of the crystal together;

Fig. 3 is a similar view of a crystal having a flat top and a concaved under surface, together with a modified means of securing the two portions of the crystal together; 60

Fig. 4 is a similar view of a crystal of the same contour as Fig. 3 but showing a different means for uniting the two portions together;

Fig. 5 is a central sectional view of a 65 crystal in which the outer surface is convex and the inner surface plain with the two portions forming the crystal separated except at their edges where they are secured together;

Fig. 6 is a similar view of a modification of Fig. 5, in that both portions of the crystal are plain, and also showing a different means for securing the two portions together, 75

Fig. 7 is a central longitudinal section of a crystal of a contour similar to the form shown in Fig. 1, but with a modified form of the means for securing the two parts together. 80

In the drawings 10 designates the inner portion of the crystal, said portion being formed of celluloid or other similar transparent, flexible, substantially un-breakable material.

11 indicates the outer portion of the crystal and is formed of glass of similar transparent, hard mar-resisting material. These two portions forming the crystal may be united together in various ways, a few of which are illustrated in the various figures of the drawings. 85

In Figs. 1, 2, 3, 4 and 7 it will be noted that the opposing surfaces of the portions 10 and 11 are in contact, so that the portion 10 forms a support for the entire inner surface of the portion 11, and increases the resistance of the portion 11 against breakage. 95

In the forms shown in Figs. 5 and 6, the two portions 10 and 11 are separated from each other, forming an air space between the two portions of the crystal which has the advantage of preventing the befogging of the crystal when exposed to sudden changes of temperature. 100

In the form shown in Fig. 1, the two portions 10 and 11 are secured together by turning up the edge 12 around the periphery of the portion 11. In this form the edge 12 stops short of the upper surface of the portion 11. In the form shown in Fig. 2 the portions are secured together by a similar 110

edge 12 which, however, is extended up over the periphery of the upper surface 11, as indicated at 13.

In the form shown in both Figs. 1 and 2 the crystal is concavo convex. In the form shown in Fig. 3 the crystal is plano-concave, and the two portions are secured together by forming a shoulder 14 on the edge of the portion 10, and providing the portion 11 with a depending flange 15, which can be snapped over the shoulder 14.

In Fig. 4 the crystal is also shown as being plano-concave, and the two portions are shown as being secured together by forming the portion 10 with a depression 16 of the diameter of the portion 11, so that a projecting rim 17 is provided on the portion 10, and when the portion 11 is snapped into the depression 16 will engage the periphery 20 of the portion 11 and hold it in position.

In Fig. 5 the portion 11 is shown as concavo convex, while the portion 10 is plano. As a consequence when these two portions are secured together an air chamber 18 is formed between them which will prevent fogging. In this figure I have illustrated these two portions as being secured together by the flange 19 formed on the portion 10 being turned over the edge of the portion 11. I have also shown the under surface of the portion 10 as provided with a depending ring 20 located just within its periphery, adapted to rest upon the face of the dial when the crystal is in position.

In Fig. 6 I have illustrated a form in which both the portions 10 and 11 are plano and separated to provide an air space 18. The two portions are shown as mounted in a ring 21 having an under portion 22 extending under the lower surface of the portion 10, an intermediate inwardly extending bead 23 extending between the portions 10 and 11 to separate them, and an inwardly beveled portion 24 engaging the periphery 45 of the portion 11, the portion 11 being snapped in under this beveled portion in the same way that a glass crystal is now commonly snapped into a bezel.

In Fig. 7 the portion 11 is shown as of a greater thickness than the portion 10, and provided with a groove 25 in its periphery into which is forced the flange 26 formed by turning up the edge of the portion 11.

In all the forms of the invention just de-

scribed it is to be noted that if the outer portion 11 is broken that the portion 10 remains intact and protects the face covered thereby.

I realize that considerable variation is possible in the details of construction and arrangement of parts without departing from the spirit of my invention, and I therefore do not intend to limit myself to the specific form shown and described.

I claim:

1. A crystal formed of two portions secured together, the outer portion being of hard, mar-resisting transparent material, and the under portion being of transparent, flexible, substantially non-breakable material.

2. A crystal formed of two portions secured together, the outer portion being of glass and the under portion being of transparent, flexible, substantially non-breakable material.

3. A crystal formed of two portions secured together, the outer portion being of hard, mar-resisting transparent material and the under portion being of celluloid.

4. A crystal formed of two portions secured together, the outer portion being of glass and the under portion being of celluloid.

5. A crystal formed of two portions, the outer portion being of hard, mar-resisting, transparent material and the under portion being of transparent, flexible, substantially non-breakable material, the edge of the under portion being turned up around the periphery of the upper portion to secure the two portions together.

6. A crystal formed of two portions secured together with their adjacent surfaces in contact, whereby the under portion will act as a support and reinforcement for the outer portion, the outer portion being of hard, mar-resisting, transparent material, and the under portion being of transparent, flexible, substantially non-breakable material.

Signed at New York, this 12th day of November, 1918.

LOUIS E. F. WACHTER.
